UNITED STATES PATENT OFFICE.

OTTO GENTSCH, OF MAGDEBURG, GERMANY, ASSIGNOR TO ERNEST ROSE, OF NEW YORK, N. Y.

CONNECTING MEMBER.

Application filed July 25, 1921, Serial No. 487,539. Renewed April 15, 1924.

To all whom it may concern:

Be it known that I, OTTO GENTSCH, a citizen of Germany, and resident of Magdeburg, Germany, have invented a new and 5 Improved Connecting Member, of which the following is a full, clear, and exact description.

My invention relates to a connecting member, and aims to provide certain new and 10 useful improvements in connection with a device of this character, and more particularly a connecting member which is utilized for establishing electrical contact between two leads.

15 It is well appreciated that any number of connecting devices have been proposed whereby for example a main line and branch lead might be secured to and in electrical contact with each other. For the most part 20 these devices have offered objections in that primarily they were incapable of permitting of quick association of one conductor to a second conductor.

Furthermore, the electrical contact established was in many instances, not efficient in that the members were not pressed into intimate contact with each other.

Where connecting members were provided which avoided the foregoing effects it was 30 found that these latter members were too heavy, and also that the same might not be manufactured at a nominal figure.

With this in mind, my present invention aims to provide a connecting member which 35 primarily may be of such a nature as to permit of the quick association of two electrical conductors, one with the other.

A further object of my invention is the 40 construction of a device of the character stated in which the contact established between the connecting members shall be of such an intimate nature as to reduce current losses at this point, to a minimum.

Still a further object of my invention is 45 the provision of a connecting member which shall be extremely simple in construction, and capable of being manufactured at a nominal figure, aside from the fact that the parts will be sufficiently rugged to withstand even abnormal usage thus eliminating 50 any objections on this point.

Still other objects of my invention will become apparent from the annexed specification taken in connection with the draw-

ings, which latter illustrate practical embodiments of the same, and in which;

Figure 1 is a side view of a connecting member embodying my improved construction and showing the same applied to a pair of conducting members.

Figure 2 is a transverse sectional view taken along the lines 2—2 and in the direction of the arrows indicated in Figure 1, and

Figure 3 is a bottom view of the member.

In these views the reference numeral 5 indicates the main conducting member which is to be tapped by the lead or second conducting member 6, both of these members being stripped of their insulation at all 70 points adjacent to the point at which they are to contact with each other.

Referring now more particularly to the connecting member it will be seen, reference being had to Figure 2 that the same preferably includes a body 7 V shaped in cross section, one of the arms 8 thereof being extended beyond the second arm, and terminating in a portion 9 lying at right angles to both of the arms of the body portion 7, 80 and being spaced from the outer end of the smaller arm.

Thus it will be seen that a space is provided, which is sufficient to permit of the passage of the conducting members 5 and 6, and, as has been illustrated in the drawings, I preferably introduce the conducting member 6 through this space into the crotch of the arms of the body portion 7, subsequent to which the entire device may be 90 hooked over the second conducting member or lead 5.

Now with a view of providing means serving to retain the parts in the position indicated it will be seen that the extended portion 9 forms what virtually might be termed a platform through which set screws 10, or other suitable clamping members may extend, the inner end of these set screws bearing against the outermost portion of the main lead 5 and pressing the same into intimate contact with the conducting member 6, a movement of this latter member being precluded by virtue of the fact that the same is wedged between the arms of the 100 body portion 7.

Thus an efficient electrical contact is established between the conducting members

5 and 6, and the whole is retained in applied position. After the clamping action of the screws 10 has been continued to a point at which this has been effected, a 10 clamping bolt 11 extending through and engaging lugs 12 and 13 associated with the end of the shorter arm and extended portion of the body of the member 7 respectively, is turned so that the lugs 12 and 13 are drawn 15 towards each other. By virtue of the fact that the bolt and lug which it engages are to one side of the line of pressure produced by the set screws 10, and conducting members 5 and 6 it will be seen that quite a leverage may be established at these points, and thus the parts are not alone locked by the set screws 10, but also by the bolt 11 so that the conducting members 5 and 6 are 20 pressed even more intimately into engagement with each other, and the set screws and body portion, whereby any current leakage will be virtually precluded, it being also noted in this connection that the parts will be more firmly locked with respect to 25 each other, thus further precluding any accidental detachment thereof.

From the foregoing it will be appreciated that the objects set forth in the preamble of this specification have been accomplished, 30 and it will further be understood that numerous modifications of structure might readily be resorted to without in the least departing from the spirit of my invention, which I claim as:

- 35 1. A connecting member for electrical conductors, including an elongate body portion V shaped in cross section, said conductors being adapted to lie in the crotch between the arms of said body portion, and
- 40 2. a plurality of independently operable means each for pressing said conductors into intimate engagement with each other and with said body portion at a different point along the length of the body portion.
- 45 3. A connecting member including a unitary body portion presenting an opening and a crotch beyond the opening permitting of said body being hooked over conductors to be clamped one atop the other in said crotch, and means co-operating with said body portion and bearing against said conductors for pressing the same into intimate engagement with each other and with said body.
- 50 4. A connecting member including a body portion presenting an opening permitting of said body being hooked over conductors to be clamped into contact with each other, means co-operating with said body portion and bearing against said conductors for pressing the same into intimate engagement with each other and with said body, further means adapted to subsequently increase

the engagement between said parts, and to close the space through which said conductors pass. 65

4. A connecting member including a body portion V shaped in cross section, one of the arms of said body portion being extended beyond the second of the same, an extended portion forming a continuation of said extended arm, and set screws projecting through said extended portion and having their inner ends substantially in line with the crotch of said body portion. 70

5. A connecting member including a body portion V shaped in cross section, one of the arms of said body portion being extended beyond the second of the same, an extended portion forming a continuation of said extended arm, set screws projecting through said extended portion and having their inner ends substantially in line with the crotch of said body portion, lugs forming continuations of said extended portion 80 and smaller arm respectively, and means co-operating with said lugs for drawing said parts toward each other. 85

6. A connecting member including a body portion V shaped in cross section, one of the arms of said body portion being extended beyond the second of the same, an extended portion forming a continuation of said extended arm, set screws projecting through said extended portion and having their inner ends substantially in line with the crotch of said body portion, lugs forming continuations of said extended portion, and smaller arm respectively, and a bolt extending through said lugs to permit of the same 100 being drawn towards each other.

7. A connecting member including a body portion presenting an opening permitting of said body being hooked over conductors to be clamped into contact with each other, means co-operating with said body portion and bearing against said conductors for pressing the same into intimate engagement with each other and with said body, and further means adapted to subsequently increase the securement of the engagement between said parts. 105

8. A connecting member for electrical conductors including a substantially C-shaped body portion, the top of the C being of inverted V-shape to provide a crotch inside and at the top of the C, said crotch for receiving said conductors in longitudinally overlapping relation, and means for compressing the conductors into intimate mutual contact and into intimate contact with the crotch, said means including a clamping instrumentality carried by and screw-threadedly adjustable on the body portion. 115

120 OTTO GENTSCH.
